UNITED STATES PATENT OFFICE

ROBERT E. DIAL, OF ROSEDALE, INDIANA, ASSIGNOR OF ONE-HALF TO HERMAN F. BRUNNER, OF ROSEDALE, INDIANA

EXPANSION BIT

Application filed November 5, 1930. Serial No. 493,639.

By way of explanation, it may be stated that it is common in coal mines, to bore a hole for a charge of power, and this invention aims to provide a novel expansion bit, 5 which, placed in the hole, can be expanded, so as to ream out a chamber at the inner end of the hole, thereby to enable the powder to be placed more advantageously for a shot.

The invention aims to provide a device of 10 the class described having novel means for controlling the lateral movement of the side bits. It is within the province of the disclosure, moreover, to improve generally, and to enhance the utility of, devices of that type to 15 which the invention appertains.

With the above and other objects in view which will appear as the description proceeds, the invention resides in the combination and arrangement of parts and in the details 20 of construction hereinafter described and claimed, it being understood that changes in the precise embodiment of the invention herein disclosed may be made within the scope of what is claimed without departing from 25 the spirit of the invention.

In the accompanying drawings:

Figure 1 shows in side elevation, a device 30 constructed in accordance with the invention;

Figure 2 is a longitudinal section wherein parts appear in elevation;

Figure 3 is a side elevation of the tool, the bits being contracted, instead of expanded as in Figure 1;

Figure 4 is an end elevation indicated by the line 4-4 in Figure 3;

Figures 5 and 6 are sections taken on the lines 5-5 and 6-6 of Figure 2.

The tool forming the subject matter of this 40 application preferably is made of metal throughout. It comprises an elongated cylindrical body 1 provided with any desired number of spiral ribs 2. The body 1 has a rectangular bore 3 which is expanded at its rear end to form a socket 4 receiving the end

on the operating member 5 whereby rotation is imparted to the tool, the operating member 5 being held in the socket 4 by any desired number of securing elements 14.

The numeral 6 designates a center bit which 50 has limited longitudinal sliding movement in the bore 3 of the body 1. The boring point 7 of the bit 6 may be of any desired construction. In the edge of the center bit 6 there is a recess 8 forming shoulders 9 and 10. A 55 stop pin 11 is mounted in the body 1 and extends across the bore 3, the above said pin extending across the recess 8 of the center bit 6 between the shoulders 9 and 10.

An abutment pin 12 extends across the bore 60 3 and is mounted in the body 1 some distance behind the rear end of the center bit 6. Against the pin 12, a compression spring 15 abuts, the forward end of the spring 15 engaging the rear end of the center bit 6. On 65 its rear end, the center bit has a finger 16 engaged within the forward end of the spring 15 and aiding in holding the spring in place.

The center bit 6 is provided with a projection 17 in the form of a block, which extends 70 around three sides of the center bit. The projection or block 17 is shown as being held in place by a securing element 18, but if desired, the projection 17 and the center bit 6 may be formed in one piece, such a change 75 requiring no specific showing in the drawings. At its forward end, the body 1 has outstanding enlargements 19, and certain of these enlargements may be formed integrally with the forward ends of the spiral ribs 2, 80 as shown in Figure 3. The enlargements 19 have slots 20 across which extend pivot elements 21. Side cutters 22 and 23 are mounted at their rear ends in the slots 20 and on the pivot elements 21, for inward and outward 85 radial swinging movement. The side cutters 22 and 23 may be beveled and sharpened at their forward ends, as shown at 26, although the cutting edges of the side cutters 22 and 23 may be formed in any desired man- 90

ner. Cams 24 are held on the side cutters 23 by securing devices 25, although the cams might be formed in one piece with the side cutters if desired. The side cutter 22 does 5 not have a cam 24.

In practical operation, the spring 15 forces the center bit 6 forwardly, until the shoulder 10 engages the stop pin 11. Under such circumstances, the side cutters 22 and 10 23 are swung inwardly, as shown in Figure 3, the side cutter 22 resting against the center bit 6, as shown in Figure 3, and the projection 17 being clear of the cams 24 on the side cutters 23 so that the said side cutters can swing 15 inwardly.

When the point 7 of the center bit 6 comes 20 into contact with the inner end of the hole that has been bored, the center bit 6 is shoved backwardly into the position of Figure 2, the spring 15 being compressed, and the shoulder 9 coming into contact with the stop pin 11. As the center bit 6 moves backwardly, the projection or block 17 co-operates with the 25 cams 24 on the side cutters 23 and swings the side cutters 23 outwardly, the side cutter 22 remaining in place near the side edge of the center bit 6, as shown in Figure 2 of the drawings. The cams 24 are so placed on the side cutters 23 that the side cutters 23 will 30 extend outwardly at different angles with respect to the center bit 6, the side cutter 22 being nearest to the center bit 6, the side cutters 23 extending outwardly at progressively increasing angles. The cutters 22 and 35 23, therefore, cut one after another, to ream out and enlarge the hole at its inner end, as the tool is rotated. After the hole has been reamed out to the desired extent, the tool can 40 be withdrawn. As soon as there is no pressure on the forward end of the center bit 6, the center bit 6 is shoved forwardly by the action of the spring 15, and then, the side cutters 22 and 23 can swing inwardly into 45 approximate parallelism with the center bit 6 as shown in Figure 3, thereby permitting the tool to be pulled out of the hole.

The device is simple in construction, but it affords means whereby a miner can ream out a blast hole readily. The device forming the subject matter of this application, 50 will enable the miner to shoot down more coal and better coal than is possible at present. The device will stand long, continued use, and will not get out of order.

Having thus described the invention, what 55 is claimed is:

1. In a device of the class described, a body, a center bit mounted for reciprocation on the body, side cutters pivoted to the body, and means associated with the center bit and with the side cutters for swinging the side cutters outwardly at different angles with respect to the center bit, when the center bit moves rearwardly.
2. In a device of the class described, a

body, a center bit mounted for reciprocation in the body, side cutters pivoted to the body, and relatively inclined parts on the side cutters and on the center bit, said inclined parts being so proportioned that, when the center bit moves rearwardly, the side cutters will be inclined outwardly at different angles with respect to the center bit.

In testimony that I claim the foregoing as my own, I have hereto affixed my signature.

ROBERT E. DIAL.
